SOLE OF SHOES

Lewis J. Bazzoni, Swampscott, Mass., assignor
to United Shoe Machinery Corporation, Paterson,
N. J., a corporation of New Jersey

Original application May 23, 1932, Serial No.
613,008. Divided and this application April 6,
1934, Serial No. 719,343

8 Claims. (Cl. 36—24.5)

This invention relates to the manufacture of shoes and is illustrated as embodied in a sole of a shoe.

In the manufacture of shoes it is customary to cover the breast of a Louis heel for example, after attachment of the same to a shoe, with a heel-breast covering flap which is split from the grain side of the rear portion of the sole of the shoe. The flap is split from the sole before attachment of the sole to the shoe and extends forwardly of the heel-breast line of the sole and throughout the width of the sole.

The heel-breast covering flap is usually of substantial thickness in order to withstand the wear to which it is subjected. After the flap has been trimmed flush with the breast edges of the heel the thick edges of the flap detract from the appearance of the shoe. Accordingly, in the better grades of shoes it is customary for the operator to thin down the marginal portions of the flap by the use of a hand knife just prior to cementing the flap to the heel breast. This is accomplished by removing material from the inner side of the flap by wide beveling cuts which start approximately at the respective ends of the heel-breast line of the flap and continue to the end of the flap, the flap being trimmed by the beveling cuts to an outline which is slightly larger than the breast of the heel. The flap resulting from such an operation is durable and is provided with thin edges which are not subject to the objection above noted. It is common practice to tuck the end portion of the heel-breast covering flap projecting beyond the top-lift receiving face of the heel under the top-lift and accordingly it is desirable to reduce the thickness of the end portion of the flap. In reducing such flaps the beveling cuts which start at the heel-breast line of the flap increase in width as they approach the end of the flap, the cuts overlapping at a point spaced from the end of the flap.

It is necessary for the operator to trim the flap to an outline slightly larger than that of the breast of the heel as he reduces the thickness of the lateral margins of the flap by beveling cuts, in order to insure that the edges of the flap when finally trimmed to the outline of the heel shall be of nearly uniform thickness. In order, therefore, to trim the flap to a shape which approximates the shape of the heel breast, the heel must be attached to the shoe preparatory to trimming the flap to a reduced outline and skiving the margins of the same. To trim the flap at this stage in the construction of the shoe is objectionable since such

trimming operation is slow and requires the services of a skilled operator. Moreover, when flaps are trimmed as above described the shape of the breasts of the covered heels vary in accordance with the beveling cuts made by the operator.

With the above considerations in view there is provided a sole including a heel-breast covering flap having at its inner side a relatively thick elongated median rib which varies in width and which has a relatively thin marginal portion the inner and outer sides of which are approximately parallel. In the illustrated construction the median rib is V-shaped the top of the V being positioned substantially at the heel-breast line of the flap. The rib which extends to a point below the projecting portion of the breast of the heel tapers gradually toward its margins and merges attractively with the relatively thin marginal portions of the flap.

The flap may be quickly and effectively reduced either before or after its attachment to the shoe by a machine such as disclosed in application for United States Letters Patent Serial No. 613,008, filed May 23, 1932 in my name, of which the present application is a division.

Since the inner and outer sides of the marginal portion of the present flap are parallel as distinguished from converging as when the flaps are trimmed by hand, it is not necessary to trim the flap to a reduced outline until after the same has been cemented to the breast of the heel since the portions of the flap which cover the lateral margins of the heel breast are of uniform thickness and therefore the thickness of the edges of the flap are the same regardless of the distance cut in from the margin of the original flap. By providing the above-defined flap which may be cheaply formed in the stock-fitting room, it has been found practicable to reduce the heel-breast flaps of shoes of cheaper grades at selected localities thereby improving the appearance of the flaps without reducing the strength of the same. Moreover, by providing the present flap the shape of the breast of the covered heel is substantially the same as the shape of the breast of the wood heel blank and the breasts of covered heels are uniform.

With the above and other objects and features in view the invention will now be described in connection with the accompanying drawing and pointed out in the claims.

In the drawing,

Fig. 1 is a perspective view of a sole provided with a heel-breast covering flap which has been split therefrom;

Fig. 2 shows the sole illustrated in Fig. 1 after the heel-breast covering flap has been reduced at selected localities in accordance with the present invention; and

5 Fig. 3 is a perspective view of the rear end of an inverted shoe including the sole illustrated in Fig. 2.

In the manufacture of shoes provided with Louis heels it is customary to split material from 10 the grain side of the rear portion of a sole 22 (Fig. 1) thereby to provide an unreduced heel-breast covering flap 24 which in the finished shoe is cemented to the breast of the heel. The flap 24 should be of sufficient thickness to prevent 15 it from being easily torn. When the unreduced flap 24 is laid upon the breast of the heel and is trimmed flush with the breast edges of the same the thick edges of the flap are of objectional appearance. It has been found by 20 experience that the area of the flap which covers the central part of the projecting laterally-convex portion of the breast of the heel should be of substantial thickness in order that the flap shall not tear or split along its heel-breast line 25 32 and shall not be worn out by rubbing the breast of the heel against objects such, for example, as the rung of a chair. It is also desirable that the portion of the flap which covers the lower part of the breast of the heel be thin in 30 order that the breast of the finished heel shall approximate as nearly as practicable the breast of the uncovered heel. Furthermore, it is sometimes the practice to tuck the end portion of the flap under the top-lift and for this further reason 35 it is desirable that the end portion of the flap be fairly thin.

With the above considerations in view it is common practice for the operator after pressing the flap by hand against the breast of the heel for the purpose of imprinting an outline of the heel-breast line upon the flap, to remove material from the inner side of the flap and to trim the flap to an outline slightly larger than the outline of the heel breast by beveling cuts each of 40 which starts at the heel-breast line of the flap 45 which starts at the heel-breast line of the flap and extends to the end of the flap. The end of the flap is also trimmed by a beveling cut when it is desired to tuck the same under the top lift of the heel. After the reduced flap has been cemented to the breast of the heel it is trimmed 50 to the outline of the breast of the same.

The hand skiving operation which is slow and requires the services of an experienced operator is not always satisfactory since the edges of such flaps are not always of uniform thickness and occasionally in making the beveling cuts the operator thrusts his knife through a portion of the flap which is to cover the heel breast. In order to eliminate the hand operation applicant 55 has provided the above-mentioned machine which is disclosed in application for United States Letters Patent Serial No. 613,008. Such machine is constructed and arranged to remove material at selected localities from the inner side of the flap either before or after the sole has been attached to the shoe. It has been found preferable, however, to remove material from the sole before the sole is attached to the shoe.

The illustrated sole which may be advantageously reduced at selected localities by the above machine is provided with a heel-breast covering flap 42 comprising a V-shaped rib 44 which is of substantial thickness and tapers toward its apex 46 as well as toward its sides from a central base 75 portion 48 thereof. The marginal portion 50 of

the flap 42 surrounding the rib 44 is of uniform thickness, the inner face 52 of the flap being substantially parallel to the grain face 54 of the flap. The lateral base portions of the V-shaped rib 44 curve sharply away from the respective edges of the flap and intersect the edges of the flap at the heel-breast line 55. The shank portion 57 of the flap is of uniform thickness throughout its extent.

5 The rib 44 which extends from the ends of the heel-breast line 55 to a point below the projecting portion of the breast of the heel is of sufficient thickness to insure that the heel-breast flap shall not split across its breast line 55 due to the flexing of the shoe during the application of walking pressure and shall not be easily worn through by engaging pressure of the projecting portion of the breast of the finished heel with different objects. It will be understood that the length of rib may be varied.

The rib 44 which extends from the ends of the heel-breast line 55 to a point below the projecting portion of the breast of the heel is of sufficient thickness to insure that the heel-breast flap shall not split across its breast line 55 due to the flexing of the shoe during the application of walking pressure and shall not be easily worn through by engaging pressure of the projecting portion of the breast of the finished heel with different objects. It will be understood that the length of rib may be varied.

After the flap has been cemented to the heel it is trimmed flush with breast edges of the heel, the edges 56 (Fig. 3) of the applied flap being thin and of uniform thickness throughout their extent.

It will be noted that regardless of the outline of the breast of the heel each of the edges 56 is of uniform thickness since the marginal portion 50 of the flap is of uniform thickness.

Having thus described my invention, what I claim as new and desire to secure by Letters Patent of the United States is:

1. A shoe sole provided with a heel-breast covering flap having at its flesh side a relatively thick longitudinal median rib which is of varying width and is beveled along its marginal portions, said flap including relatively thin lateral marginal portions of sufficient length to extend from the top to the bottom of a heel to which the flap is to be secured, the inner face of each marginal portion being approximately parallel to the outer face of such portion and forming a substantially continuous surface with the heel engaging face of the rib.

2. A shoe sole provided with a heel-breast covering flap having at its inner side a relatively thick elongated median rib which varies in width throughout substantially its entire length, said flap having relatively thin lateral marginal portions, the inner and outer sides of which are approximately parallel.

3. A shoe sole provided with a heel-breast covering flap having at its inner side an elongated median rib which extends lengthwise of the flap and which is of decreasing width from the heel-breast line of the flap, said flap also including a thin marginal portion which surrounds the rib and is defined by inner and outer surfaces arranged approximately parallel to each other.

4. A shoe sole provided with a heel-breast covering flap having at its inner side a substantially thick elongated rib which extends over a substantial portion of the width of the flap in the vicinity of the heel-breast line of the flap and tapers widthwise as it extends toward the end of the flap, said flap having relatively thin lateral marginal portions the inner and outer sides of which are approximately parallel to each other.

5. As a new article of manufacture, a boot or shoe sole having its rear end portion divided horizontally throughout its width and adjacent to the tread side thereof from the back of the heel part 70 forwardly into the shank part a substantial distance beyond the position to be occupied by the breast of a heel, said sole being provided with a thin breast-covering flap having at its inner side a narrow relatively thick longitudinal median rib 75

of varying width which is beveled along its marginal edges, and provided with a relatively thin side marginal portion formed at each side of the rib and of sufficient length to extend from the top to the bottom of the heel, the inner side of each side marginal portion of the flap being approximately parallel to the outer side of such portion and forming a substantially continuous surface with a corresponding beveled margin of the rib.

10 6. As a new article of manufacture, a boot or shoe sole having its rear end portion divided horizontally throughout its width and adjacent to the tread side thereof from the back of the heel part forwardly into the shank part a substantial distance beyond the position to be occupied by the breast of a heel, said sole being provided with a thin breast-covering flap having at its inner side a narrow relatively thick longitudinal median rib of varying width which is beveled along its marginal edges and provided with a relatively thin side marginal portion formed at each side of the rib and of sufficient length to extend from the top to the bottom of the heel, the inner side of each side marginal portion of the flap being approximately parallel to the outer side of such portion and forming a substantially continuous surface with a corresponding beveled margin of the rib and the shank portion of the flap being of greater thickness than said marginal portions and having inner and outer surfaces which are approximately parallel.

25 7. As a new article of manufacture, a boot or shoe sole having its rear end portion divided horizontally throughout its width and adjacent to the

tread side thereof from the back of the heel part forwardly into the shank part a substantial distance beyond the position occupied by the breast of a heel so as to provide a thin breast-covering flap, said flap having upon its inner side a narrow relatively thick longitudinal median rib and formed at each side of said rib with a relatively thin side marginal portion of a length to extend from the top to the bottom of said heel, the inner and outer faces of each side marginal portion being approximately parallel and the shank portion of said flap being of greater thickness than said side marginal portions and having inner and outer surfaces which are approximately parallel.

10 8. As a new article of manufacture, a boot or shoe sole having its rear end portion split horizontally throughout its width and adjacent to the tread side thereof from the back of the heel part forwardly into the shank part a substantial distance beyond the position of the breast of the heel so as to provide a thin breast-covering flap, said flap having upon its inner side a narrow relatively thick longitudinal median rib and formed at each side of said rib throughout the length of the latter with a relatively thin side marginal portion of sufficient length to extend from the top to the bottom of a heel, the inner and outer surfaces of each side marginal portion being approximately parallel and the shank portion of said flap being of greater thickness than said side marginal portions and having inner and outer surfaces which are approximately parallel.
